AUTOMATIC CRANKSHAFT GRINDING AND
POLISHING MACHINE

Elmer Alvin Fuglie and Hilton John Anderson,
Winona, Minn., assignors to Winona Tool Mfg.
Company, Winona, Minn., a corporation of
Minnesota

Application June 4, 1943, Serial No. 489,708

9 Claims. (Cl. 51—123)

Our invention relates to machines for automatically grinding and polishing shaft bearings, such as crank shaft bearings, and has for its object to provide a machine wherein the bearings of the crank shafts may be ground to true circular cross-sections entirely automatically without the intervention of human hands for any purpose excepting to change the grinders and polishers from one bearing to another.

Crank shafts, as is well known, embody two types of bearings. The first of these are known as main bearings and the axial center of these bearings forms the center of rotation of the crank shaft. The main bearings also are of two types, the end bearings and, where four, six, eight, or twelve cylinder crank shafts are involved, a series of inner bearings more or less in number according to the number of cylinders of the motor which the crank shaft serves. The second type of bearings are the rod bearings, sometimes called the throw bearings, which are offset axially from the axial center of the main bearings and thus in a rotation of the crank shaft describe with their axes a series of circles concentric with the axis of the crank shaft.

Heretofore in grinding these crank shaft bearings it has been practiced to mount a motor and shaft carrying a grinder disc upon a support adapted for rocking and sliding movements and to hold the face of the grinder against a bearing of the crank shaft. The grinder is connected with a motor and rotated by it. While the grinder is so held and rotated, the crank shaft itself will be turned about the axial center of the main bearings in the manner in which it will turn when in normal operation in a motor. The result is that the face of the grinder is rotated upon a surface of a bearing, and, if it is a rod bearing it is at the same time itself rotated so that the grinder is continuously presented to a part of the whole circumferential area of the bearing.

The grinding tool in practice is cylindrical, of small diameter and usually with a central hole in or through it. The grinding action is effected by contact of the exposed plane face of the tool contacting the bearing, and, since the bearing is or is made to become a cylinder, that contact must be along successive longitudinal elements of the cylindrical surface. It follows that to do the work effectively and produce a suitable bearing surface the plane of the face of the grinding tool must be exactly parallel to the axial center of the main bearings and also of the throw or rod bearings when the latter are being ground. It has been a very grave difficulty in past prac-

tice to obtain this absolute parallelism. For exceedingly small deviations therefrom will result in grinding tapered bearings, which, even though the taper be exceedingly small, cannot in use give satisfactory results.

10 Serious difficulties also have heretofore been encountered in so supporting the grinder and the motor for operating it that the movements in rocking and sliding of that support will be continuously effective and certain and satisfactory in operation. These difficulties have been due to the fact that there has been irregular wear of the grinder support, permitting or causing the grinding tool to get out of alignment, that there has been jamming and sticking of the parts and frequent breakages requiring replacements.

20 Another serious difficulty in the operation of crank shaft grinders is in getting the grinder face proper to operate over the entire circumferential area of the crank shaft bearing. It is of the utmost importance that the grinding operation be effective and complete for the entire circumferential area of the bearing. That is, for the whole length of the bearing from one side wall to the other.

25 It is impractical and usually impossible to get a grinding tool of a diameter exactly that of the length of the bearing, and even if such a tool could be developed and used, such a wide tool would not true the shaft bearing effectively for its whole width. So in practice it has been customary to make the grinder of a diameter much less than the length of the bearing, and for an operative to move the grinder back and forth on the crank shaft bearing along the support on which the grinding apparatus is slidably mounted.

30 This movement of the grinder itself has been in an arc of a circle not along an element of the cylindrical surface of the bearing and hence not parallel to the axial center of the main bearings and rod bearing which is being ground. So, while this operation may bring measurably good results, it depends a great deal on the skill of the 35 operator, it takes up an operator's time, and it cannot do the satisfactory work that is accomplished by moving the grinder face back and forth in right lines along the elements of the cylindrical surface of the bearings and at all times parallel to its axial center. This difficulty has been encountered both for the main bearings and for the rod or throw bearings.

40 There has also been great difficulty in properly lining up the plane face of the cutting tool with the axial center of the main bearing while these

bearings are being ground. This difficulty has been almost insuperable because variances of only a fraction of a thousandth of an inch have produced unsatisfactory work and it has been almost impossible to get machining of the tool holding means precise enough to overcome that difficulty.

Another difficulty, or at least disadvantage, has been in polishing and buffing of the bearing after it has been ground. This has been customarily accomplished independently of the grinding operation and it also has required an operator to control the polishing belt and cause it to move from side to side along the length of the crankshaft bearing.

It is, therefore, a primary object of our invention to provide a machine for truing, grinding, and polishing crank shaft bearings, which at the same time will overcome all of the above-noted difficulties and disadvantages of present practice and which will be entirely automatic throughout.

Specifically it is an object of our invention to provide in conjunction with a longitudinal polished supporting shaft a plate member having a cylindrical extension mounted upon said rod for easy sliding movement along the same and for rocking movements upon it and to carry on said plate a supporting bar member having parallel faces engageable with rollers carried by the plate member so that the supporting member may be held for oscillating movement in conjunction with the oscillation of the plate member and for sliding movement along said rollers.

It is a further object of our invention to provide such a supporting member with a pair of projecting boss-like structures to which the tool and operating motor support are connected, and to support the same through a compression spring by which the pressure of the grinder on the crank shaft bearing is regulated.

It is a further and highly important object of our invention to provide means for moving the lathe chucks or holders in conjunction with a crank shaft held thereby back and forth longitudinally a distance sufficient to cause the face of the grinder automatically to be moved back and forth across the surface of the crank shaft bearing for the full length thereof.

In carrying out the last-named object, it is a further object to provide means for progressively, successively, and continuously operating to move the chucks or work holders, together with a crank shaft held thereby, longitudinally a given distance and for reversing the operation of the same at the end of a suitable distance of travel in either direction.

It is a further object of our invention to provide simple and effective means for bringing the face grinding tool, whether used for grinding main bearings or rod bearings, into parallel relation with the axial centers of the main bearings.

It is a further object of our invention to provide buffing or polishing means operative upon the surface of a crank shaft bearing and to be shifted along the length thereof by reason of the aforesaid shifting of the chucks or work holders and the crank shaft held thereby back and forth longitudinally.

It is a further feature of our invention when grinding main bearings, in conjunction with other features of the invention hereinbefore described, to employ a powerful magnet to aid in holding the main bearing in fixed and unyielding

axial alignment with the face of the grinding disc.

The full objects and advantages of our invention will be given in detail in the appended specification, and the novel features of the invention by which the aforesaid highly advantageous results are secured will be particularly pointed out in the claims.

In the drawings illustrating an application of our invention in one of its forms:

Fig. 1 is a part perspective side elevation view of our crank case grinder.

Fig. 16 is a perspective side elevation view of the parts shown in Fig. 15, including the tripper arm and magnet.

Fig. 17 is an end elevation view of the tripper arm.

Fig. 18 is a transverse sectional elevation of a part of the stand similar to the part shown in Fig. 4, with means for automatically shifting the grinding tool back and forth on a throw or rod bearing.

Fig. 19 is an enlarged side elevation view of the upper part of the mechanism shown in Fig. 18 for causing automatic lateral travel and reversal of the tool operative in grinding rod or throw bearings.

Fig. 20 is a sectional view taken on line 20—20 of Fig. 18.

Fig. 21 is an enlarged plan view showing the means of adjustment of the transverse rod support for the motor and tool carrier for holding the face grinder in operative position.

Fig. 22 is a sectional view taken on the line 22—22 of Fig. 21.

As best shown in Figs. 1, 3, and 4, a lathe frame is provided consisting of heavy casting supports 15 and 16 secured to and supporting a heavy cap 5 piece 17 which is hollow to form a chamber 18. This cap piece is provided with end standards 19 and 20 formed with bottom flanges 21 and 22 which engage and are bolted to corresponding flanges 23 and 24 formed on the upper portions 10 of heavy casting supports 15 and 16.

The casting supports 15 and 16 are secured in parallel relation by diagonal struts 15a and 16a, which are welded at their ends to the supports 15 and 16 and may be welded together at their 15 cross point. The casting supports 15 and 16 may further be held in parallel relation by a bearing shaft 25 rather close to the bottom and a second shaft 26. These shafts will preferably be immovably united at their ends with the bodies 20 of casting members 15 and 16, the union being effected by any desired method, such for example, as welding. A third shaft 27, which has a highly important function in the applicants' machine is held to the supporting castings 15 and 16 by clamping keepers 28 and 29 bolted to 25 sides of said supporting castings. Keeper 29 is especially constructed to provide for an important adjustment later described herein.

At the left hand end of the lathe frame adjacent the supporting casting 16, a powerful connecting bracket 30 is secured to the cap piece 17. The cap piece is provided with an opening 31 on its inner side. The casting 30 has a plate 32 with a rectangular projecting portion 33 which engages with its edges the edges of the opening 31. The casting 30 also is provided with a central web 34, Fig. 6, through which extends an angularly disposed hole 35. A bolt 36 has a bent portion 37 screw-threaded toward its end, as indicated at 38, which extends in and along the hole 35. The bent portion 38 of bolt 36 continues in a horizontal portion 39 to a head 40 fast thereon. The head 40 takes against a clamping plate 41. A wing nut 42 is threaded upon the threaded portion 38 of angularly extended bolt portion 37 and may be turned to apply great force upon the clamping plate 41 by means of the transverse wing arms 43. By these means the casting 30 is removably and adjustably secured in a very strong and rigid manner to the cap piece 17 of the lathe frame.

The casting 30 at the end of web 34 is provided with an elongated bearing boss 44, shown in its outer length in Fig. 1, and in cross-section in Fig. 6. Within the boss 44 is an extended bearing cylindrical surface 45. A chuck shaft 46, Figs. 3 and 6, is held in said bearing and normally free to rotate and slide endwise therein. The bearing boss 44 is, however, longitudinally split at 47, as indicated in Fig. 6, and a bolt 48 enables the bearing to be loosened or tightened as conditions may require.

A second elongated bearing boss 49 is in all respects identical with the bearing boss 44 and houses a chuck shaft 50, Figs. 1 and 8. The bearing boss 49 is carried by a bracket 51 in all respects the same as the bracket 30, being held to the cap piece 17 in the same way, as clearly shown in Fig. 4. The shaft 46 extending through bearing boss 44 is provided with a chuck head 52, Figs. 1 and 3, and the chuck shaft 50 similarly is provided with a chuck head 53, the two chuck heads facing each other as clearly shown in Fig. 1. A crank shaft 54 having customary main end

bearings 55 and main center bearings 56, and intervening crank or throw bearings 57, Figs. 1 and 4, is adapted to be held between the two chuck heads 52 and 53. Adjustment for holding different lengths of bearings will be made by moving bracket 51 along the side of cap piece 17 in either direction, and nice adjustments for that purpose may be made by sliding the supporting shafts 50 of chuck head 53 in its long bearing 49.

Fast on the end of chuck shaft 46 is a pulley 58 over which runs a belt 59 which also runs over a pulley 60 driven by a motor 61. This motor, together with gear case 62, rests upon a shelf 63 extending from main upright casting 16 and having a bracket support 64, as indicated in Figs. 1 and 3. It follows that when the crank shaft 54 has its ends locked to the chuck shafts 46 and 50 and these shafts receive driving power from the motor 61 through the pulleys 58 and 60 and the driving belt 59, the entire assemblage including the main bearings 55, 56 and the crank bearings 57, will all be rotated about the axial center line through the chuck shafts 46 and 50, which is in alignment with the axial centers of the main bearings. When the crank shaft 54 is so rotated it will be obvious that the main bearings 55 and 56 will be rotated about their axial centers, but the crank shaft rod bearings will partake of a combination movement including in effect a rotation about their axial centers and a planetary rotation bodily about the axial center of the main bearings. The crank shaft grinder, when its face is presented to the crank shaft rod bearings must, therefore, partake of that same planetary motion. That is, a motion in a circle, which necessitates the oscillation of the grinder and its support back and forth, and in connection with that rotation an in and out linear movement to maintain the face of the grinder in contact with the surface of the rod bearing.

As shown in Figs. 1, 3, 4 and 5, a plate 65 is provided with an elongated boss 66 which is formed with a smoothly milled inner cylindrical bearing surface 67. This cylindrical bearing is 45 mounted upon the smoothly milled and polished shaft 27. When so mounted it has freedom of movement to slide along the shaft and to oscillate about the axial center of the shaft. A sliding support 68 which is rectangular in cross-section and may be wider than it is thick, as shown in Figs. 1 and 3, or may be square in cross-section, as shown in Fig. 5, is mounted upon and carried by the plate 65. The mounting shown in Figs. 3 and 4 comprises a keeper 69 which takes over the 55 back and along the sides of the bar 68 and holds it with its back against the outer face of the plate 65. Pairs of rollers 70, Fig. 4, and 71, Fig. 3, are mounted at right angles to the plate 65 and engage the sides of the sliding support 68. The support thus is mounted to slide back and forth with very little frictional resistance.

In the form shown in Fig. 5, a pair of rollers 72 and 73 are journaled at the ends of the plate 65, so that the bottom of sliding support 68 will engage those rollers, and a roller 74 is journaled at the top of the sliding support 68 in place of the keeper 69 and engages that top. So in this form of mounting of the sliding support 68 on the plate 65, all four sides of the square sliding support are engaged by rollers which results in substantially eliminating any frictional resistance.

The sliding support 68 has a pair of extension bosses 75 and 76, Figs. 3 and 4, in which is mounted a sliding shaft 77. The shaft 77, as best shown in Fig. 4, has an extension 78, which passes

through a cylindrical opening in a boss 79 extending from a carrier casting 80 in which is extended longitudinally a grinder shaft 81 having thereon a face grinder 82 of well-known construction, formed with a flat top grinding face 83. The extension 78 is provided with an adjustable hook member 84, Fig. 4, formed with rollers 85 and 86 adapted to engage the surface of a crank shaft rod bearing 57. A thumb nut rod 87 operates to extend and retract the shaft 77 carrying the hook 84 so as to bring the rollers on hook 84 and the face 83 of grinder 82 in contact with the surface of the crank shaft rod bearing 57, and the pressure of the grinder 82 against said surface may be regulated by means of the thumb nut 87 and is controlled by a compression spring 89 surrounding the rod 77 between a washer 90 fast on the rod 77 and a second washer 91 which rests upon a boss 92 fast on the carrier casting.

Upon rod 25 is slidably mounted an elongated bearing 93 fast on a plate 94 which carries a motor 95. From a pulley 96 on the shaft of said motor mounted outside of plate 94, a belt 97 drives a second pulley 98, and a wide pulley 99 on a pulley shaft 100, drives a buffer and polishing belt 101 which will extend over a crank case rod bearing 57 as shown in Figs. 1 and 4. A motor 102 is mounted on a block 103 on the carrier casting 80. The driven shaft 81 of the motor 102 rotates the grinder 82.

From the above arrangement it will be apparent that the grinder 82 may be applied to any of the crank shaft main bearings 55 and 56 and to any bearings 57, and that simultaneously the buffer and polishing belt 101 may be applied to any other crank shaft bearing. When the motors 95, 102, and 61 are all put in operation, simultaneously the crank shaft 54 will be rotated, the grinder shaft 81 and grinder 82 will be rotated in a plane at right angles to the axial line of the crank shaft rod bearing 57 to which said grinder has been applied, and the buffing and polishing belt 101 will be driven to effect buffing and polishing of the crank shaft bearing to which it is applied.

Means is provided for causing the two chuck shafts 46 and 50 and the crank shaft held thereby to move back and forth in the long bearings 44 and 45. This means is operated during simultaneous turning of the chuck shafts and crank shaft held thereby. To accomplish this I provide a gear case 104 having a back wall 105, Figs. 12 and 13. This back wall is provided with a bearing boss 106 which receives the end of chuck shaft 50, as indicated at 107 in Fig. 13. The end of the chuck shaft is in effect journalled in this bearing boss 106, and rotates freely therein while it is adapted to slide therealong. The gear case 104 is provided with a wall 108 having the shape indicated in Fig. 9. A removable cover 109 is secured to the edge of this wall by screw bolts 110 enclosing a chamber 111 within the gear case 104.

In axial alignment with the chuck shaft 50 is a shaft extension 112 which goes through an opening in the back of the gear case 104 and toward the top of the chamber 111, as clearly shown in Figs. 9 and 13. This shaft extension may be formed integrally with chuck shaft 50 or may be coupled to it in any suitable manner so as to be rotated by the rotation of the chuck shaft 50, which rotation, as above-described, takes place by reason of said chuck shaft 50 being coupled to chuck shaft 46 by a crank shaft held between the two chuck shafts.

The shaft extension 112 is coupled at 114, Fig.

13, with a threaded shaft member 115, which has a bearing at 116 in a boss 117 on the cover 109 of the gear box 104. The shaft extension 112 is threaded as indicated at 118. Any other suitable means of coupling the shaft extension 112 to the shaft member 115 so the latter may be driven by the former is contemplated and within the scope of my invention. The means of connection shown at 114 causes the shaft extension 115 to be freely rotatable relative to the shaft 112 but at the same time so as to effect longitudinal movement of the shaft 112 whenever the shaft 115 with gear case 104 is caused to move longitudinally. Any suitable form of coupling to accomplish this result may be employed. A satisfactory form is indicated in Figs. 13 and 14, where a circumferential groove 153 is formed about the reduced coupling member 114 on extension shaft 112, and screw members 154 extend into the groove 153, coupling the threaded shaft 115 to extension shaft 112 so that it may rotate independently thereof while it has a connection for longitudinal drag on it and on all parts carried by it.

As best shown in Figs. 8 and 10, the shaft extension 115 is adapted to have engaged with the threads 118 thereon, half threads indicated at 119 on the underside of a swinging connector block 120 which is adapted to be locked in engaging position by means of a bolt 121 which passes through a lug arm 122. This lug arm is provided with a sleeve 123 which is mounted on an anchor shaft 124 and which engages an annular member 125 and is locked thereto and to the anchor shaft 124 by means of a nut 126 threaded on the end of the anchor shaft 124.

The latter is rigidly connected with the bracket 51 supporting the long bearing 49, and which bracket is rigidly connected to the cap member 17 of the frame, as indicated in Fig. 8. It follows that when the shaft extension 115 is rotated and the parts are coupled together as indicated in Figs. 8 and 10, the shaft extension 115 and parts connected therewith, including the gear case 104 and the chuck shafts 50 and 46 connected together by the intermediately positioned crank shaft 54, will be advanced or retracted according to the direction of rotation of the shaft 115.

The gear case 104 is at all times restrained from turning with the chuck shaft 50 and extension shafts 112 and 115 by a bar 155 secured to the top of the gear case wall 108 by means of bolts 156. Any other suitable means for preventing turning while permitting back and forth movement may be employed. As shown, the member 155 has a horizontal part 157 which engages in a notch formed in an upstanding projection 158 on a bar 159 secured by bolts 160 to the top of the bracket 51. The horizontal part 157 of arm 155 can slide freely in the notch on the upstanding member 158 but is thereby held from turning and so holds from turning the gear case 104 and parts associated therewith, while at the same time leaving these parts free to be moved in the axial line of the chuck shaft bearings. Screw plugs 160 close oiling openings leading to the gearing in the gear case chamber 111.

As best shown in Figs. 9, 12, and 13, a pinion sprocket 127 is fast on shaft extension 112 within the chamber 111 inside gear box 104. A gear assemblage is mounted in chamber 111 toward the bottom thereof upon pin shaft supports 128 and 129, which are carried by a block 130, Fig. 12, mounted for sliding movements inside of chamber 111 along back wall 105 thereof. The slidable

block 130, as clearly shown in Figs. 12 and 13, is supported upon a stud 131 which extends through a slot 132 in the lower part of the back wall 105 of the gear case. The stud 131 is secured to a second sliding block 133 mounted to slide along the surface of a recess 134 formed in the outside of said back wall as clearly shown in Fig. 12. The outside block 133 has secured thereto a projecting block 135. Eye-bolts 136 and 136' are held in rigid adjusted position in the projecting block 135 by means of set screws 137. The eye-bolts are pivotally connected at 138 and 138' with the respective armature arms 139 and 139' of solenoids 140 and 140', Fig. 6 spring arms 177, 177' respectively engage opposite ends of the block 133 tending to keep the block in a central neutral position.

Upon the pin-shaft 128 are mounted a sprocket wheel 141 and a gear 142, and on the pin shaft 129 are correspondingly mounted a sprocket wheel 143 and a gear 144, Fig. 12, such wheel and gear being connected together to rotate in unison. The gears 142 and 144 mesh as clearly indicated in Figs. 9 and 12. Running over the sprocket pinion 127 and sprocket gears 141 and 143, is a sprocket chain 145.

It follows that when the chuck shaft 50 is rotated and in turn rotates the shaft extension 112, the sprocket pinion 127 will drive the sprocket wheels 141 and 143. The sprocket wheel 143 being rigidly connected to gear 144, said gear 144 will be rotated by the wheel 143 and said gear being in mesh with the gear 142 which is freely rotatable in mesh with the gear 142, said gears 142 and 144 will rotate in opposite directions.

A spur gear 146 is mounted to rotate freely on shaft extension 112, Figs. 9 and 13. One or the other of gears 142 or 144 may be brought into mesh with the freely rotatable large gear 146 according to the position of the slide 130 that carries the pin shafts 128 and 129. Since the sliding of the block 130 is in effect about the axis of shaft extension 112, this movement will not interfere with the drive of gears 142 and 144 and a shift in driving the large gear 146 from gear 142 to 144, or vice versa, will immediately reverse the direction of rotation of gear 146.

Upon spur gear 146 is mounted a pin 147 which projects out over the second shaft extension 115. A second pin 148 goes through shaft extension 115 and projects from it so as to be contacted at one side or the other by pin 147. It follows that when the block 130 slides the pin 131 along the slot 132 it will unmesh one of the gears, as gear 144, Fig. 9, and mesh gear 142 with the large gear 146, which will immediately reverse the direction of rotation of gear 146 and bring the pin 147 into contact with the opposite side of pin 148. This will, of course, reverse the direction of rotation of threaded shaft extension 115.

The sliding of the block 130 is brought about by energizing and de-energizing the solenoids 140 and 140', and this is accomplished through closing and breaking of one or the other of the circuits directly brought about by contact with the walls of the crank shaft rod bearing or main bearing. Having reference to Figs. 2, 15, and 17, a crank shaft main bearing is indicated at 150 having side walls 151 and 152. On a stand 161, Figs. 15 and 16, is rigidly connected a normally horizontal bar 162. The bar 162 has pivotally connected to its end by means of a bolt 163 and a head 164 a depending plate member 165. This plate member may be swung laterally, as indicated in dotted lines in Fig. 15, and in its vertical posi-

tion will overlie a side of the crank shaft bearing being ground.

The lower end of depending plate member 165 has pivotally connected thereto, as indicated at 166 and 166', a pair of make-and-break swinging fingers 167 and 167'. The upper ends of these members are provided with contact pieces 173 and 173'. Wires 179 and 179' connect with the relays 169 and 169', and other wires 172 and 172' connect with contacts 173 and 173', all as shown in Figs. 17 and 19. The contacts 173 and 173' are adapted to engage corresponding contacts 174 and 174' on the relays 169 and 169', respectively. A link 175 pivotally connects the swinging fingers 167 and 167'. Their ends 167a and 167b are positioned between side walls 151 and 152 of a main bearing 150, as clearly indicated in Fig. 17. Normally, the contacts 173 and 173' are held out of engagement with contacts 174 and 174'. When, however, an end 167a or 167b of the swinging fingers 167 or 167' contacts a bearing wall 151, it will swing the contact 173 or 173' into engagement with relay contact 174 or 174', and current will then go through the relay, energizing it and holding the switch closing contact 173 or 173' in switch closing position until it is forcibly moved away from contact, thus breaking the circuit.

When a main bearing of the crank shaft as an entirety is moved endwise with the chuck shafts by the means heretofore described, assuming the movement is to the right, as indicated in Fig. 17, the end 167a of finger 167 will be caused to contact the main bearing face 151, which will swing the member 167 on the pivot 166 to cause the contact 173 to engage the relay contact 174. This will close the circuit, which, as shown in Fig. 2, passes through the relay 169. The solenoid will then act to slide the block 130 connected by stud 131 with block 133 which in turn is connected with armature actuated member 135, as clearly shown in Fig. 12. This movement is against the force of spring 177 surrounding the chuck shaft 50 and engaging the outer block 133, Figs. 11 and 12 at both sides.

The effect of this will be to connect the gear 146 in chamber 111 of gear case 104 to drive gear 146 and turn threaded extension shaft 115 in a clockwise direction for causing the threaded engagement of 118 with the half threads 119 on arm 120 to pull the chuck shafts and crank shafts held between them to the left, as viewed in Figs. 8 and 17. This will carry the end 167a of finger 167 away from the face 151. But the relay 169 will continue to hold the contact piece 172 in circuit-closing position.

In time, however, the end 167b of finger 167' will engage the face 152. This engagement will simultaneously swing the levers 167 and 167' on pivots 166 and 166' and pull the contact 173 out to break contact with relay 169, and at the same time close the circuit through contacts 173' and 174'. When this happens the solenoid 169 will be de-energized and the solenoid 169' will be energized and will push the block 133 and the parts connected therewith in the opposite direction, thus unmeshing gear 142 and meshing gear 144 with large gear 146 and turning threaded screw 115 in the opposite or counter-clockwise direction to cause the screw 115 to turn in a counter-clockwise direction which will reverse the movement of the parts. That is, the chuck shafts and crank shaft held by them will again travel to the right, as viewed in Figs. 8 and 17. And the reversing operations will be repeated and continue to be repeated until one crank shaft bearing has been suf-

ficiently ground and another crank shaft bearing has been buffed and polished. The operation will then be stopped and the grinder tool and polishing belt will be applied to other crank shaft bearings.

When the current is cut off for stopping operation, or if, at any time, current is cut off, spring arms 177 and 177', Figs. 11 and 12, engaging the ends of the sliding block 133 will swing the same and with it the gears 142 and 144 into neutral position as shown in Fig. 9 when both of these gears are out of mesh with the large gear wheel 146 and no further operation of the back and forth movement of the chuck shaft, and crank shaft held between them can take place, even if these parts continue to be driven from motor 61. This is a safety feature, protecting against possible breakage of parts.

The above description of automatic operation has been related to the main bearings, which have only rotation about their several axes. But we contemplate the automatic shift back and forth of the grinder tool against the surface of the rod or throw bearings as well as against main bearings. The simple means of effecting this, using principally substantially the same devices which operate the back and forth automatic movement for main bearings, are shown in Figs. 18 to 20.

As there shown, the carrier bar 68 with its bosses 75 and 76, the plate 65 for supporting it, and the rollers 70, 71, 72, 73 and 74 are unchanged. In place of the rod 77 mounted to slide and oscillate in the bosses 75 and 76, we provide here a different type of rod 205, which, as shown in Fig. 20, is rectangular in cross-section, preferably square, and which is adapted to slide longitudinally in square openings 206 extending through the bosses 75 and 76. This restrains the grinder carrier 80 and connected motor 102 from oscillating on the carrier 68 and holds them in fixed alignment. This arrangement, while restraining the carrier 80 and parts connected with it, from oscillating laterally with respect to the carrier 68 which is held locked against such oscillation by the rollers 70, 72, and 74, will, nevertheless, at the same time permit free longitudinal up and down movement as well as oscillating movement of the carrier bar 68 and free longitudinal movement of the tool carrier 80 under adjusted compulsion of spring 89 to force the face of grinder tool 87 at all times against the surface of a rod bearing 57.

The special bar 205 has an extension 207, Fig. 18, to which a part 208 of the hook member is rigidly secured. The roller bearings 209 which engage the surface of rod bearing 57, are in this fixed hook arm 208. And the movable hook arm 210 is held in adjusted position with its roller 210' in engagement with the rod bearing 57 by means of the spring 211 controlled by adjusting thumb screw 212.

The extension 207 carrying the relays 169 and 169' and the contact making fingers 167 and 167' and also carrying the part 208 and the hook member and rollers, is removably secured to the rod member 205 as indicated at 219 in Fig. 18, and thus may be removed when it is desired to use the apparatus for grinding main bearings.

The extension 207 goes to a high point at 213 and has secured to the opposite sides thereof brackets 214 and 215 which carry the relays 169 and 169', heretofore described, excepting that these relays are attached to and move with extension 207 of rectangular bar 205. These members and their contacts and their relation to the make-and-break fingers 167 and 167' are identically the

same as when these elements are associated with a main bearing. The ends 167a and 167b of the make and break fingers 167 and 167' are, as shown in Fig. 19, positioned so as to come between the 5 rotating faces 216 and 217 of a rod or throw bearing 218. The wires 170 and 172 for relay 169 and 170' and 172' for relay 169' will normally be brought together in a flexible cable which will permit the movement of the extension 207 as above 10 outlined without interfering with the electrical circuits to the relays 169 and 169' and to the solenoids 140 and 140'.

The operation for grinding crank shaft or throw bearings and for automatically shifting them longitudinally to produce automatic grinding of the whole surface of these bearings, will not vary substantially from that described for the main bearings. The only difference will be that the 15 extension member 207 and the contact making fingers 167 and 167' will partake of the identical rotating and sliding movements of the carrier member 68. The same effective and certain grinding will take place, automatically made to cover the entire length of the rod or throw bearing between the side walls thereof, and will be effected for the throw bearings as it is effected for the main bearings.

The relays 169 and 169' are small and not heavy, and the oscillation of these relays will not 20 affect in any way their capacity to make these contacts. It will be noted that the fingers 167 and 167' are of spring metal and can yield while the slight gaps 220 and 221 between the contacts 173, 174 and 173' and 174', are open. This action 25 will follow the shifting of the fingers in either direction which, because of the link 175, must shift together. It follows that when that shifting is effected in either direction it simultaneously breaks one of the contacts and remakes the other 30 contact, and this will be true whether the apparatus is grinding main bearings or rod or throw bearings.

In order to have the automatic grinding of either main or throw bearings completely effective, it is necessary that the face of the grinder 87 be parallel to the central axis of the particular crank bearing which is being ground, which 35 means necessarily that the plane of the face shall be parallel with the central axis of the main bearing. To mill carriers such as 205 and their supports, sufficiently accurately to be absolutely certain to effect this parallelism, is almost, if not wholly, impossible. Yet we have discovered that 40 a very slight angular relation between the face 45 of the grinder and the axis of the bearing will produce a tapered bearing which will be unsatisfactory in use no matter how smooth and true otherwise the grinding may be. An important 50 feature of our invention is the means we employ to overcome this difficulty.

As heretofore pointed out, the plate 65 for holding the oscillating and sliding carrier 68, or 205, is mounted to slide along a straight polished bar 27 secured to the sides of members 15 and 16 by 55 keeper plates 28 and 29 secured thereto. The keeper plate 29 as shown in Fig. 22, is secured to the side of upright supporting member 15 by means of bolts 222 and 223 which pass through elongated holes 224 and 225 formed in keeper flanges 226 and 227. The keeper base 228 engages a raised flat face 229 and is held by the bolts 230 and 231 passing through lugs 232 and 233, set out from the ends of said flattened face portion 229. The ends of the bolts 230 and 231 60 engage the ends of flange portions 226 and 227.

By loosening bolts 222 and 223 and screwing bolts 230 and 231 the keeper 29 may be moved longitudinally in one or the other direction, up or down, along the mounting surface 229. This will result in shifting the carrier 68 or 205 to 5 correspondingly shift the face of the grinder tool 87 by which means said face may be brought exactly into parallel relation with the axis of the main bearings and of the rod bearings.

Referring to Fig. 2, it will be apparent that 10 current goes from line wires 178 and 179. Following the current from wire 178 through wires 180 and 181, the current goes to drive motor 61 and through wire 182 to grinder motor 102. Current from drive motor 61 returns to line wire 179 15 by wire 183 and switch wire 184, and current from grinder motor 102 returns to line wire 179 through wire 185 and switch wire 184. A supplemental circuit carries current from line wire 172 by wire 186 through solenoid 176'. A branch wire 186' from wire 186 connects with solenoid 176. Wire 170 extends between relay 169 and solenoid 176 and wire 170' extends between relay 169' and solenoid 176'. Through a wire 187, in circuit with the contacts 173 and 173', a branch wire 184 and main switch 188, the current returns to the main line wire 179 whenever either of the relay contacts 174 or 174' are closed. The main switch 188 is the on-and-off switch for the entire 20 apparatus. The buffer motor 95 will be in the same circuit, not shown, and may have a supplemental switch to put it out of operation when desired.

As already indicated, there are two types of 35 main bearings to a crank shaft, end bearings such as the bearings 55 indicated in Fig. 1, and center bearings, such as the bearing 56 also indicated in Fig. 1. The number of center bearings depends, of course, upon the type of motor which is employed. In Figs. 1 and 4 a simple four-cylinder motor crank shaft has been shown. Obviously, for six, eight, and twelve-cylinder motors there would be larger numbers of interior main bearings.

Inasmuch as the crank shaft must be supported as a whole merely from its ends, there is serious difficulty in holding the interior main bearings firmly and certainly in alignment, due to the natural sag which comes from a long piece of heavy steel. On the other hand, there is no practical way to put a direct support under such interior main crank shaft bearings. We have discovered that this problem is effectively met by using a powerful magnet engaging the main bearing from above and holding it firmly against rollers on the armature of the magnet.

This arrangement is shown particularly in Figs. 15 and 16. As there shown, a casting attachment 190 (which carries the stand 161 already described) is adapted to be secured adjustably as to longitudinal position, to the top rail 17 of the lathe in a manner similar to the means of securing the bearings for the chuck shafts to the same member. As shown in Fig. 15, the casting 190 is provided with a bolt 191 which passes through a plate 192 and has a nut 193 and a cross pin 194 outside of the casting 190 and the plate 192, respectively. By screwing upon the nut 193, the casting attachment 190 can be securely attached to the top rail 17 in any desired position along it. Between the stand arms of the stand 161 is mounted a strong magnet 195 which is energized by wire 196 leading to it. The magnet has an armature 197 upon which are rollers 198, Fig. 15, adapted to engage

a main interior bearing 56 directly at the top thereof. Any other suitable mounting of the magnet will be within the scope of our invention.

When the magnet 195 is energized the attraction through armature 197 will hold the main crank shaft bearing 56 firmly against the rollers 198, in this manner supporting a substantial part of the weight of the crank shaft and enabling accurate grinding thereof without danger of dishing because of sagging of the shaft. Other parts are in general not substantially different from those heretofore described. However, since the carrier bar 68 does not require to be slid up and down or oscillated as is true when crank shaft rod bearings are being ground, I have found in practice that it is desirable, when grinding main bearings, to secure the carrier 68 against any movement. This I do by securing to a lug 199 on member 190 a link 200, which is preferably rigidly secured to lug member 199 and this link in turn is firmly secured at 201 to a lug 202 on the carrier bar 68.

Since the position of the magnet and the center of its field of attraction may affect the axial line of the main bearing, we have provided special means for making an adjustment to bring the center of the field of attraction of the magnet directly in the vertical plane passing through the true axis of the main bearing being ground. The effect of this is to further insure that the plane of the face of the grinder 82 will be parallel to the axis of the main bearings 56 or 150. We accomplish this correction with simple but unusual means.

The shaft 27 upon which is mounted the bearing 66 of the bracket 65 for supporting the grinding means is milled very true and round as is the interior bearing 66, so that the carrier may move back and forth along the shaft 27 with a suitable degree of ease. To insure that grindings will not get into the bearing and tend to wear it and also to produce friction, we provide a bagging indicated at 203 and 204 of Fig. 1 to protect the shaft and keep all of the grinding dust away from it.

The member 190 is an ordinary casting which is formed with laterally disposed openings 234 and 235, Fig. 16. Slit-like openings 236 and 237 are formed extending from end points 238 and 239 of the casting into the openings 234 and 235. This leaves a central pedestal 240 of the cast metal with a depending portion 241 provided with laterally extended arms 242 and 243 below the kerf or cut-out portions 236 and 237 and also separated by only the thickness of said kerf by top arms 244 and 245. Screw bolts 246 and 247 are threaded through these arms as clearly shown in Fig. 16.

We have discovered that by turning up on one 60 of these bolts and turning down on the other bolt, there is enough yield to the metal of the pedestal 240 so that the entire casting above that pedestal may be shifted laterally. This shift, though small in actual amount, will be sufficient 65 to carry the vertical plane of the magnet's field into the vertical plane passing through the axial center of the main bearing, which will cause the pull of the magnet to have the effect of placing that center line in parallel relation to the plane 70 of the top face of the grinder.

While we have described the magnetic supporting arrangement as applied to main bearings, and in general it is designed to be used in connection with the grinding of main bearings, in 75 the grinding of throw bearings on long shafts

it may be desirable to support the crank shaft magnetically from the immediately adjacent main bearing. This, of course, is done exactly as above described, with the application of no additional means, but it will tend to hold the entire crank shaft and all of the crank bearings thereon, including the throw bearings, as well as the main bearings, at all times parallel with the true horizontal axis of the main bearings.

The advantages of my invention have been made to appear in general in connection with the detailed description given in the foregoing specification. A fundamental and primary advantage resides in the fact that perfect grinding of crank shaft bearings, either main bearings or rod bearings, can be effected absolutely automatically, and, at the same time and with the same operation of rotating the crank shaft, the buffing and polishing of the various bearings may take place. While we have only shown a single grinding unit and a single buffing unit, it will be obvious that any desired number of grinding units may be assembled upon the supporting rod 27 and correspondingly any desired number of buffing units may be assembled on the supporting rod 25, and all of said units be caused to operate simultaneously upon one crank shaft. In such an assemblage there will need to be only one of the stands 161 and swinging contact levers 167 for controlling the oscillation back and forth of the crank shaft in conjunction with the chuck shafts holding the same.

Also, it is an essential and particular advantage of our invention not only to make our machine operate entirely automatically for grinding and polishing one or more crank shaft bearings simultaneously, but very materially to improve the grinding and polishing operation. This is effected in a highly satisfactory manner by the longitudinal back and forth movement of the crank shaft as held by the chuck shafts, so the grinding tool and the polishing tool may be successfully presented over the whole length and the entire circumferential area of each bearing which is being ground. It is further advantageously effected by the means provided which make possible placing the face of the grinder absolutely parallel with the axes of the bearings. And means for doing that is provided for both main bearings and rod or throw bearings.

It is a highly important advantage of our invention that this oscillation of the crank shaft is effected by its rotation through simple and effective means controlled by the make-and-break of solenoid circuits through alternate engagement of the make-and-break fingers with the opposite side walls of a crank shaft bearing.

A further great advantage of our invention resides in the fact that the grinder assemblage, including the motor for rotating the grinder tool, is so mounted on the supporting shaft that it may readily be moved from one bearing to another and that its oscillating and rocking movements are substantially all controlled by contacts with roller guides.

It is a further great advantage of our invention that the grinding of main interior bearings of the crank shaft, and also of throw or rod bearings, is made exceptionally certain and sure by giving an overhead support for the crank shaft at said bearings through the operation of a powerful magnet presented to the bearings at that point.

We claim:

1. In a crank shaft grinder, a pair of aligned

5 chuck shafts mounted for joint rotary and longitudinal movements when a crank shaft is locked to said chuck shafts, means for rotating the chuck shafts and crank shaft held thereby, means including a gear driven by the rotation of the chuck shafts and crank shaft held by them for moving them longitudinally as they are being rotated, and means for reversing the direction of rotation of said gear to cause reversal of said longitudinal movement, and means associated with the side walls of a crank shaft bearing for controlling said direct and reverse longitudinal movements to limit them in extent to the length of the crank shaft bearing being ground.

10 2. In a crank shaft grinder including a pair of aligned chuck shafts mounted for joint rotary and longitudinal movements when a crank shaft is locked to said chuck shafts, means to move and to reverse longitudinal movement of said chuck shafts and crank shaft while rotary movement continues, comprising a gear box, a train of gears therein driven by a rotating chuck shaft including a pair of gears constantly driven in opposite directions, a floating gear adapted to be meshed with either of said oppositely rotating gears to be driven thereby in opposite directions, and means for connecting said floating gear operatively to the chuck shaft assemblage to cause the same to be moved endwise forward and back as the oppositely driven gears are successively meshed and unmeshed with the floating gear.

15 3. In a crank shaft grinder including a pair of aligned chuck shafts mounted for joint rotary and longitudinal movements when a crank shaft is locked to said chuck shafts, means to move and to reverse longitudinal movement of said chuck shafts and crank shaft while rotary movement continues, comprising a gear box, a train of gears therein driven by a rotating chuck shaft including a pair of gears constantly driven in opposite directions, a floating gear adapted to be meshed with either of said oppositely rotating gears to be driven thereby in opposite directions, means including a solenoid, and means for connecting said floating gear operatively to the chuck shaft assemblage to cause the same to be moved endwise forward and back as the oppositely driven gears are successively meshed and unmeshed with the floating gear.

20 4. In a crank shaft grinder, a grinding tool and means for rotating it, supporting means to hold the grinder against a bearing while the crank shaft is being rotated, constantly driven means for moving the bearing endwise back and forth, and means including solenoids and electric circuits for operating them for causing regular reversal of movement to limit said back and forth movement to the length of the bearing, said means including circuit make and break devices, and fingers for operating the same engageable with the side walls of the bearing to effect such reversal.

25 5. A crank shaft grinder comprising a plane-faced grinding tool and sliding and oscillating means for supporting the same so that said face may be continuously presented to the surface of a rod bearing while the crank shaft is being rotated, said means including a hook device riding upon said bearing, an extension of said last-named means, a pair of relays mounted on said extension, a pair of solenoids operative for gear shifting, a circuit for said solenoids, and means to make and break said circuit including fingers mounted on said extension and adapted to be

successively engaged by the side walls of said rod bearing.

6. A crankshaft grinder tool, comprising means for holding and rotating a crankshaft about its axial center, a grinder having a plane face, means for rotating the grinder and for holding its face against an intermediate main bearing of the crankshaft as it is rotated, magnetic means having its field of attraction positioned above the crankshaft and operative to aid in its support to hold it for rotation about its axial center, and means for moving said magnetic means so as to cause its maximum lifting field to lie in the vertical plane of the axis of the bearing and to hold said bearing so that the axis thereof will be parallel to the plane of said grinder face.

7. In a crankshaft grinder, means for holding a crankshaft including a pair of aligned chuck shafts with means for locking the crankshaft thereto, said chuck shafts and crankshaft being mounted for combined rotary and longitudinal movements, means for rotating the chuck shafts and the crankshaft held thereby, a gear connected to one of the chuck shafts and rotated thereby, means connected with said gear including a threaded shaft for moving the chuck shafts and crankshaft held by them longitudinally when the latter are being driven, and means for reversing the direction of rotation of said gear to cause reversal of rotation of the threaded shaft and effect reversing of the direction of longitudinal movement of the chuck shafts and crankshaft.

8. In a crankshaft grinder, means for holding a crankshaft including a pair of aligned chuck shafts with means for locking the crankshaft thereto, said chuck shafts and crankshaft being mounted for combined rotary and longitudinal

movements, a grinder tool having a plane face, means for simultaneously rotating the grinder tool and holding its face against the surface of a crankshaft rod bearing held by the chuck shafts while the same is being rotated, a gear connected with one of said chuck shafts including a threaded shaft for moving the chuck shafts and crank shaft held by them longitudinally as they are being rotated, and means rendered operative by the longitudinal movements of the rod bearing for reversing the direction of rotation of said gear to cause reversal of rotation of the threaded shaft and thus to effect reversal of the direction of longitudinal movement of the chuck shafts and crankshaft.

9. In a crankshaft grinder, a supporting frame having end standards, means thereon for holding a crankshaft including a pair of aligned chuck shafts with means for locking the shaft thereto, 20 means for rotating the chuck shafts and the crankshaft held thereby, a shaft member extending between and supported upon the standards, a grinder frame having a part mounted on the shaft member for rocking and lateral movements thereon, a grinder carried by the grinder frame having a plane face held thereby to engage a crankshaft bearing, means for operating the grinder while the crankshaft is being rotated, lugs on one of the standards, a keeper holding 25 an end of said shaft against the standard between said lugs, and means carried by the lugs for making close adjustment of the keeper to move the end of the shaft up or down to bring the face of the grinder carried by the grinder frame into a 30 plane parallel with the axis of the rod bearing. 35
